CLAIM

The ornamental design for a connector to battery, as shown and described.

DESCRIPTION

FIG. 1 is a perspective view of a connector to battery showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof; the left side elevation view being a mirror image;

FIG. 7 is a sectional view thereof, taken along line 7—7 of FIG. 2;

FIG. 8 is a sectional view thereof, taken along line 8—8 of FIG. 2; and,

FIG. 9 is a perspective view of a connector to battery showing a corresponding battery for use. The broken lines in FIG. 9 are included for the purpose of illustrating environmental structure only and form no part of the claimed design.
